UNITED STATES PATENT OFFICE.

CHARLES MARSHALL MUMFORD, OF NEWTON CENTER, MASSACHUSETTS.

CHUTE.

Application filed August 10, 1921. Serial No. 491,126.

To all whom it may concern:

Be it known that I, CHARLES M. MUMFORD, a citizen of the United States, residing at Newton Center, in the county of Middlesex and State of Massachusetts, have invented certain new and useful Improvements in Chutes, of which the following is a specification.

This invention relates to chutes of the general character used widely in industrial plants and the like to convey material from one point to another. The invention will be herein disclosed as embodied in a spiral chute since especially difficult problems arise in the construction and operation of these chutes, although it will be appreciated from an understanding of the invention that many of its features are applicable also to other forms of chutes.

Usually where a chute is employed simply to transport articles from an upper to a lower floor, a spiral construction is employed since it occupies relatively little space. These chutes generally are constructed of sheet metal and are customarily built in standard pitches; that is, four feet to a turn, six feet to a turn, or some other fixed distance, and the gradations between pitches is usually a substantial distance. The result is that only rarely is a chute of exactly the right pitch for a given location. Usually it is necessary to select the standard pitch that comes closest to that desired. Furthermore, these chutes usually are not "banked" but, instead, the elements of the bottom surface are substantially horizontal. A fairly heavy article, therefore, which presents relatively little friction as it slides down the chute will travel very rapidly and will be urged outwardly against the outer wall of the chute, due to centrifugal force. For some purposes this action is not objectionable, but in other cases, as for instance in textile mills, where boxes filled with bobbins are transported in this manner, the heavier loaded boxes are likely to gain such speed that the bobbins will be thrown out of them. This excessive speed also results in breaking the boxes when they come in contact with others at the bottom of the chute.

A further objection to these prior constructions is that the factors to be taken into consideration in designing a spiral chute for most locations are so many and they affect the design in so many particulars, that

a chute is rarely absolutely correct when it is first assembled. When once set up it cannot be adjusted, and it is therefore necessary, if it is not reasonably satisfactory, to take it down and put up another chute based on the experience gained in the first installation.

With these factors in view, it is the chief object of the present invention to devise a chute construction which shall be more universal in character than those heretofore available. The invention is directed particularly to providing a construction which can be adjusted after it has been installed, and which shall have a relatively wide range of adjustment so that it can be used in a great variety of locations and can be adjusted to the requirements of each individual location. The invention also aims to devise a form of chute which can be manufactured more economically than prior constructions.

The nature of the invention will be readily understood from the following description when read in connection with the accompanying drawings, and the novel features will be particularly pointed out in the appended claims.

Referring now to the drawings, Figure 1 is a perspective view of a spiral chute constructed in accordance with the present invention;

Fig. 2 is a cross sectional view of a portion of the chute shown in Fig. 1; and

Fig. 3 is a side elevation of the parts shown in Fig. 2.

The chute shown in the accompanying drawings comprises two bottom rails designated at 2 and 3, respectively, and two side rails 4 and 5, respectively, these rails being spaced to form a guideway for a box or other carrier or article. The rails may be either solid or hollow but preferably consist of pipes or tubes since this construction has ample strength for most purposes and is much lighter than solid rails.

The spiral part of the chute is supported by a pipe or column 6 which forms the axis of the spiral and has its lower end mounted in a suitable base 7. The rails are mounted in a series of supporting units which are spaced apart longitudinally of the chute. Each of these units comprises a set of parts, the detailed construction of which is best shown in Figs. 2 and 3. As shown in these figures each of these units includes a split

clamping collar 8 encircling the post 6 and clamped thereon by bolts 9 and 10. A sector-like plate 12 is secured to this clamp by the bolts 10 and forms a support for an adjustable arm 14 having a flat shank which is secured to the side of the plate 12 by bolts 15 and 16. It will be seen from an inspection of Figs. 1 and 3 that the bolt 15 forms a pivot for the arm 14, and that the bolt 16 can be placed in any one of a series of holes 17 formed near the outer edge of the plate 12 and located along an arc struck about the axis of the bolt 15. This construction thus permits the adjustment of the arm into various positions of inclination.

The rails 4 and 5 are supported by brackets 18 and 19, respectively, the bottom portions of these brackets consisting of split clamps which embrace the tubular part of the arm 14, and are clamped thereon by bolts 20. The bottom rails 2 and 3 are similarly supported by brackets 22 and 23 which also have split clamps formed integral therewith to embrace the tubular portion of the arm 14, these clamps being secured to the arm by bolts 24. Each of the rails 2 to 5 inclusive is gripped in a clamp 25 having a head that is grooved, as shown at 26, to receive the rail, and is split downwardly from the base of the groove. A bolt 27 extends through these split portions at right angles to the axis of the seat 26, and serves to spring the two jaws of the clamp 25 toward each other and to compress them on the rail and hold it securely. It will be seen that the seat 26 has a circumferential extent of somewhat over 180° so that the clamp will embrace the rail and grip it securely when the bolt 27 is tightened up, but will leave the inner surface of the rail free for contact with the articles conveyed by the chute. Each of these rail holding devices or clamps 25 also has a shank consisting of two ears 28 by means of which it is secured to the bracket on which it is mounted. The brackets 18 and 19 that support the side rails are each provided at its upper or outer end with a lug 29 which is located between the ears 28, and these ears and the lug 29 are secured together by a bolt 30. In order to connect the rail holding device 25 for the bottom rails 2 and 3 with their cooperating clamps 22 and 23, each of these clamps has a boss formed in its upper side which is drilled and tapped to receive the threaded shank of an eye bolt 32, the head of which is located between the ears 28-28 and is secured to these ears by a bolt 33.

It will now be observed that each of these rail holding devices 25 has a universal adjustment. That is, referring for instance to the device which holds the rail 5, Fig. 3, it will be seen that this device can be

adjusted angularly in a horizontal plane by movement about the bolt 30 as an axis; it can also be angularly adjusted in a vertical plane about the axis of the arm 14, and it can be moved in another vertical plane at right angles to the two planes just mentioned by swinging the arm 14 on its axis 15. The other device which holds the rail 4 has similar movements, and the holding devices for the rails 2 and 3 can also be adjusted in the same manner, the angular adjustment in a horizontal plane taking place about the axes of the eye members 32. In addition to these adjustments, the rail holding devices can be adjusted toward or from each other on the arm 14, and all these devices can be adjusted in unison by adjusting the arm 14 about the bolt 15. This arm can also be adjusted in a horizontal plane about the axis of the column 6 and it can be raised or lowered on the column.

These adjustments, therefore, permit any reasonable variation in the cross sectional dimensions of the chute, in the pitch of the spiral, and in the banking angle of any given portion of the chute. Consequently, it is an easy matter to set up this chute in approximately its desired condition and then adjust it, or any portions of it, as may be necessary to accommodate the conditions encountered. For instance, in making a spiral chute to carry bobbin boxes, as above mentioned, the parts preferably are adjusted so that the boxes come into the spiral in a substantially level position, and the banking angle of the chute increases gradually during the portion of the chute in which the speed of the box is increasing. The banking angle reaches its maximum at about the point that the speed of the box becomes substantially constant and this banking angle is maintained throughout the greater part of the chute, the angle and the pitch being gradually reduced near the bottom of the chute so that the box will slow up and assume a level position as it reaches the straight-away at the delivery end of the chute. In this manner the box will rest on its bottom during its entire travel through the chute, its contents will not be thrown out, and its speed will be checked at the lower part of the chute so that it will not be broken when it bumps into boxes previously delivered.

As above stated, however, the conditions vary widely with different installations and the nature of the article being conveyed, and the wide range of adjustability afforded by this construction is of great practical advantage in permitting the adjustment of the chute to meet these various conditions. Furthermore, this adjustment can be made after the chute has been set up and tried out, and it can be continued until suc-

sive adjustments and trials demonstrate that the proper condition has been reached.

While the invention has been herein disclosed as embodied in a spiral chute, it will readily be appreciated that it is not limited to embodiment in this particular form of chute, but that many of its features may be used to advantage in other chutes, whether straight or curved, the supports for the rail holding devices being selected in accordance with the circumstances existing in individual installations. It will also be understood that the invention is susceptible of embodiment in forms other than that specifically disclosed herein without departing from the spirit or scope of the invention.

What is claimed as new is:

1. In an apparatus of the character described, the combination of a plurality of rails extending substantially parallel with and closely adjacent to each other and cooperating to form a chute, and means supporting said rails for adjustment to vary the relationship between them.

2. In an apparatus of the character described, the combination of a plurality of rails extending substantially parallel with and closely adjacent to each other and cooperating to form a chute, and means supporting said rails for adjustment to vary the cross sectional dimensions of the chute.

3. In an apparatus of the character described, the combination of a plurality of rails extending substantially parallel with and closely adjacent to each other and cooperating to form a chute, and means supporting said rails for adjustment to modify the pitch of the chute.

4. In an apparatus of the character described, the combination of a plurality of rails extending substantially parallel with and closely adjacent to each other and cooperating to form a chute, and means supporting said rails for adjustment to modify the banking angle of the chute.

5. In an apparatus of the character described, the combination of a plurality of rails extending substantially parallel with and closely adjacent to each other and cooperating to form a chute, and devices supporting said rails in their operative positions and enabling them to be adjusted both in unison and also individually.

6. In an apparatus of the character described, the combination of bottom and side rails cooperating to form a chute, and a plurality of sets of rail supporting devices spaced apart longitudinally of the chute and supporting the chute, each of said sets including a support adjustable angularly in a plane transverse to said chute.

7. In an apparatus of the character described, the combination of bottom and side rails cooperating to form a chute, a plurality of sets of parts supporting said rails at in-

tervals spaced along the chute, each of said sets comprising brackets for supporting the bottom and side rails, a common support on which the brackets of each set are mounted, and means whereby said support may be adjusted angularly in a plane transverse to the chute.

8. In an apparatus of the character described, the combination of bottom and side rails cooperating to form a chute, a plurality of sets of parts supporting said rails at intervals spaced along the chute, each of said sets comprising brackets for supporting the bottom and side rails, an arm on which said brackets are mounted for adjustment toward and from each other, and means supporting said arm for angular adjustment in a substantially vertical plane.

9. In an apparatus of the character described, the combination of bottom and side rails cooperating to form a chute, a plurality of sets of rail supporting devices spaced apart longitudinally of the chute and supporting the chute, each of said sets including a plurality of rail holding devices and a common support for said devices, and a mounting for said support enabling it to be adjusted in a plane transverse to the chute.

10. In an apparatus of the character described, the combination of a plurality of rails cooperating to form a chute, a plurality of sets of parts supporting said rails at intervals spaced along the chute, each of said sets comprising brackets for supporting the individual rails, and a common support on which the brackets of each set are mounted.

11. In a rail chute, the combination of a rail holding device, and means supporting said device for universal adjustment.

12. In a rail chute, the combination of a rail holding device, and means supporting said device for adjustment in planes extending at substantially right angles to each other.

13. In a rail chute, the combination of a rail holding device, and means supporting said device for adjustment in three planes extending at substantially right angles to each other.

14. A spiral chute comprising an upright column, a series of supporting units mounted on said column, and a plurality of rails supported by said units and cooperating to form a spiral chute, said units comprising means adjustable to vary the banking angle of the chute.

15. A spiral chute comprising an upright column, clamps secured to said column at vertically spaced intervals, arms supported by said clamps for angular adjustment in a substantially vertical plane, brackets adjustably mounted on said arms, and bottom and side rails supported by said brackets and cooperating to form a chute.

16. A spiral chute comprising an upright

column, clamps secured to said column at vertically spaced intervals, arms supported by said clamps for angular adjustment in a substantially vertical plane, brackets 5 mounted on said arms, and a rail holding device adjustable on each bracket, said devices supporting a plurality of rails cooperating to form a chute.

17. A spiral chute comprising an upright 10 column, clamps secured to said column at vertically spaced intervals, arms supported by said clamps, brackets mounted on each of said arms for adjustment both toward and from each other and angularly about the 15 arms, and rails supported by said brackets and cooperating to form a chute.

18. In an apparatus of the character described, the combination of a plurality of rails cooperating to form a chute, a plurality

of sets of parts supporting said rails at intervals spaced along the chute, each of said sets including members supporting individual rails for adjustment relatively to each other, and a common support for said members.

20
25
19. A spiral chute comprising an upright column, a series of supporting units mounted on said column, and a plurality of rails supported by said units and cooperating to form a spiral chute, said units being adjustable to vary the pitch of the chute.

20
30
20. In a rail chute, the combination of a rail holding device constructed to grip a rail while leaving one side thereof free for the contact therewith of the articles conveyed 35 by said chute, and means for adjustably supporting said device.

CHARLES MARSHALL MUMFORD.
